Patented June 4, 1918.

UNITED STATES PATENT OFFICE.

LOUIS E. ARMSTRONG, OF PENSACOLA, FLORIDA.

TORPEDO TRAP OR GUARD.

1,268,419.

Specification of Letters Patent.

Patented June 4, 1918.

Application filed July 25, 1917. Serial No. 182,759.

To all whom it may concern:

Be it known that I, LOUIS E. ARMSTRONG, a citizen of the United States of America, residing at Pensacola and State of Florida, have invented certain new and useful Improvements in Torpedo Traps or Guards, of which the following is a specification, reference being had therein to the accompanying drawing.

10 This invention relates to a torpedo trap or guard, and has for its principal object the production of an improvement upon my prior application filed March 29, 1917, and bearing Serial Number 158,339.

15 Another object of this invention is the production of a torpedo trap or guard which is provided with simple and efficient supporting means for the primary net so arranged as to permit this net to be lifted 20 clear of the water when the same is not in use.

Another object of this invention is the production of a torpedo trap or guard which is provided with an efficient supporting 25 means for the tanks, whereby when so desired the supporting means may be elevated for facilitating the lifting of the tanks to a point adjacent the sides of the ship.

30 A still further object of this invention is the production of a torpedo trap or guard which is provided with an efficient supporting means for the primary net, arranged so as to cause the net to be at all times carried adjacent the water, while the same is in use, 35 and which is provided with forked arms for checking the inward swinging motion of the net when the same is struck by a torpedo.

With these and other objects in view this invention consists of certain novel combinations and arrangements of parts, as will be 40 hereinafter fully described and claimed.

In the accompanying drawing:

Figure 1 is a side of a portion of the torpedo trap or guard, showing the same mounted upon a ship and in position for use.

Fig. 2 is a front elevation of a portion of the torpedo trap or guard.

Fig. 3 is a fragmentary sectional view through a portion of one of the tanks, and 50 supporting means for one of the free arms, illustrating the manner in which the clamps are employed in retaining these arms in set positions.

Fig. 4 is a section taken on line 4-4 of 55 Fig. 1, looking in the direction of the arrow.

Fig. 5 is a fragmentary sectional view

through a portion of the primary net, illustrating the manner in which a lifting cable is woven therethrough.

By referring to the accompanying drawing by numerals, it will be seen that the torpedo trap or guard is to be used upon the hull 1 of a ship. This hull 1 is provided with a longitudinally extending shaft 2, carried in any suitable manner by brackets 3 60 mounted within the hull 1, while this shaft 2 will be rotated by any suitable driving means, not being deemed necessary to be herein shown. The finger 4 is keyed in any suitable manner upon the shaft 2, so that when the 65 shaft is rotated, rotary motion will be imparted to this finger. The hull 1 is provided with a slot 5 formed therethrough, so as to permit the finger 4 to communicate with the exterior portion of the hull, as shown in 70 Figs. 1 and 4. Tracks 6 are secured in direct relation upon the outer side of the hull 1, and have overhanging flanges 7 which fit upon the elongated plate 8, slidably mounted upon the outer side of the hull 1. Thus, it 75 will be seen that the flanges 7 will hold the plate against accidental displacement, and as this plate is provided with an internal rack 9, which meshes with the finger 4, the plate may be moved in a vertical plane by the 80 rotation of the finger.

The tank 10 is provided with an eye 11 to which one end of the retaining link 12 is secured, as shown at 13. The opposite end of this link 12 is secured by an eye 14 to the 90 lower end of the plate 8. In this manner it will be seen that the tank 10 will be held at a spaced distance from the side of the hull 1 when the tank is resting in the water. The cable 15 is secured as shown at 16 to the tank 95 10, so that when desired the cable 15 may be drawn inwardly upon the ship thereby raising the tank 10, while the finger 4 may be raised by the shaft 2, thus, causing the plate 8 to be lifted and in this manner cause the 100 tongue to be elevated to any position above the water line desired, even to positioning the tank at a point adjacent the outer surface of the hull 1. The tank 10 may be provided with a propeller 17 which may be operated 105 by any suitable mechanism positioned within the tank or at any other point desired, for relieving the hull, of the strain involved in propelling the torpedo trap or guard through the water.

An upwardly projecting arm 18 is fixedly mounted upon the tank 10, so as to be secured

to the primary net. This primary net comprises a plurality of foldable sections, comprising outer strands 19 and inner strands 20, and these strands 19 and 20 are engaged 5 by transversely extending strands 21. The sections of the net are secured together by links 22, whereby an elongated net having a broad area is constructed which may be folded when not in use. The arm 18 is secured 10 to the upper section of the net, thus, holding the net in spaced relation with respect to the tank 10. In order to hold the arm 18 from swinging downwardly when supporting the weight of the net, there is 15 provided a coil spring 23, which has one end secured to the upper section of the net, as shown at 24, while the opposite end of this coil spring 23 is secured as indicated at 25, to the hull of the ship. A cable 26 passes 20 downwardly over the outer strand 19 of the upper section of the net, and this cable 26 is then passed around to extend upon the opposite sides of the net, as shown clearly in 25 Figs. 1 and 5. This cable 26 may be provided with a plate 27 engaging the lower section so as to prevent the cable from slipping through the net, as the cable is being wound in any suitable manner upon the ship. It is, of course, obvious that as the 30 cable is wound upon the ship, it will be drawn upon the lower sections and will cause the cables to be folded upward somewhat in "fan-like" manner, so that when the ship is sailing under ordinary conditions the primary 35 net may be carried above the water line. At this time the propulsion power of the tank will cause the tank to move along without the necessary dragging action by the ship. Upon sighting a torpedo or when 40 passing through some restricted area, the cable 26 may be released, and at this time the weight of the sections of the net will cause the net to move downwardly. It will be noted that the clamp ears 28 are riveted, or 45 otherwise fixedly secured, as shown at 29 to the tank 10, and that the upper end of the arm 30 extends between these ears, so as to be held in engagement with these ears 28, by the clamping of these ears upon the arm 30, 50 as the bolt 31 is clamped in set position in engagement with the ears 28, as illustrated in Fig. 3. It will be noted that the arm 30 is considerably longer than the arm 18 and projects outwardly and normally at a spaced 55 distance from the net. The arm 30 is provided with a plurality of fingers 32 adjacent its lower end in alignment with the lower portions of the net. As a consequence, when the net is struck by a torpedo the force imparted 60 will drive the net to each of the fingers 32 which will engage the net, and limit the swinging movement of the net. In this manner the net will yield to the force of the torpedo. It is obvious that the speed of the 65 torpedo will be reduced and by the time the

net engages the finger 32 and its movement is limited the torpedo will be finally stopped. As soon as the pressure is relieved from the net, it will return to its normal position, as shown in Fig. 1.

70

If so desired an auxiliary net 33 may be carried by the eye 11 of the tank 10, or any other suitable point upon the tank, so as to extend downwardly between the hull 1 of the ship, and the arm 30 mounted upon the tank 10.

As has been hereinbefore set forth the net may be retained above the water line, when it is not in use, or if so desired the cable 15 may be drawn on to the ship, while the 80 plate 8 may be lifted, so as to cause the entire guard to be carried above the water line. When so desired, however, the plate may be locked and the cables 15 and 26 unreeled for causing the tank to rest upon the 85 surface of the water for holding the sectional net in its correct position, for engaging the torpedo. While only one tank has been described, it is of course obvious that it is intended to use a net of continuous construction extending around the entire ship, thus, necessitating the mounting of a number of tanks and the operating elements necessary for the proper force of each tank, although it is not thought necessary to make 95 such a disclosure in the present case, since it would merely be a repetition of the disclosure made in connection with the tank.

From the foregoing description it will be seen that a very efficient torpedo trap or 100 guard has been produced, which will be carried adjacent the water line when in use, or which may be moved upwardly to a point adjacent the side of the hull of the ship, when not in use. It will further be seen 105 that an efficient means is provided for lifting the sectional net above the water line, while permitting the tanks to remain in the water, so as to allow the net to be almost instantly reduced to an operative position, 110 while an efficient arm is provided upon the net for limiting the inward swinging movement of the net, thereby causing the movement of the torpedo to be retarded or stopped.

115 What is claimed is:

1. In a torpedo trap or guard, the combination of a tank, an arm extending from said tank, a net carried upon said arm, a second arm projecting from said tank and being normally spaced from said net, and said last mentioned arm being adapted to limit the swinging movement of said net, when the same is struck by a torpedo.

2. In a torpedo trap or guard, the combination of a tank, means for supporting said tank at a spaced distance from the hull of a ship, an arm projecting from said tank, a net carried upon said arm, a second arm projecting from said tank, fingers formed upon 130

said last mentioned arm, and said fingers being adapted to engage said net, when said net is swinging in one direction, whereby the swinging movement of the net in one direction may be limited.

5. In a torpedo trap or guard, the combination of a plate, means for lifting and lowering said plate, a tank, means for connecting said plate to said tank, a net supported by said tank, and said tank being adapted to be lifted by said plate, when not in use.

10. In a torpedo trap or guard, the combination of a shaft, tracks mounted upon said shaft, a plate slidably mounted upon said tracks, said plate having a rack, a finger engaging said rack means for retaining said

finger, whereby said plate may be raised or lowered, a link connecting said tank to said plate, a net supported by said tank, and said plate being adapted to move upwardly for 20 elevating said tank, when so desired.

15. In a torpedo trap or guard, the combination of floating means, means for supporting said floating means upon a ship, a sectional net carried upon said floating means, 25 and a cable interwoven through said sectional net, whereby said cable may be drawn so as to fold said net when so desired.

In testimony whereof I hereunto affix my signature.

LOUIS E. ARMSTRONG.
